(57) **CLAIM**

The ornamental design for a battery, as shown and described.

DESCRIPTION

FIG. 1 is a front elevational view of a first embodiment of a battery of the design;

FIG. 2 is a rear elevational view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a first perspective view thereof; and

FIG. 8 is a second perspective view thereof;

FIG. 9 is a front elevational view of a second embodiment of a battery of the design;

FIG. 10 is a rear elevational view thereof;

FIG. 11 is a top plan view thereof;

FIG. 12 is a bottom plan view thereof;

FIG. 13 is a right side elevational view thereof;

FIG. 14 is a left side elevational view thereof;

FIG. 15 is a first perspective view thereof; and

FIG. 16 is a second perspective view thereof;

FIG. 17 is a front elevational view of a third embodiment of a battery of the design;

FIG. 18 is a rear elevational view thereof;

FIG. 19 is a top plan view thereof;

FIG. 20 is a bottom plan view thereof;

FIG. 21 is a right side elevational view thereof;

FIG. 22 is a left side elevational view thereof;

FIG. 23 is a first perspective view thereof; and
FIG. 24 is a second perspective view thereof;
FIG. 25 is a front elevational view of a fourth embodiment
of a battery of the design;
FIG. 26 is a rear elevational view thereof;
FIG. 27 is a top plan view thereof;
FIG. 28 is a bottom plan view thereof;
FIG. 29 is a right side elevational view thereof;
FIG. 30 is a left side elevational view thereof;
FIG. 31 is a first perspective view thereof; and
FIG. 32 is a second perspective view thereof;
FIG. 33 is a front elevational view of a fifth embodiment of
a battery of the design;
FIG. 34 is a rear elevational view thereof;
FIG. 35 is a top plan view thereof;
FIG. 36 is a bottom plan view thereof;
FIG. 37 is a right side elevational view thereof;
FIG. 38 is a left side elevational view thereof;
FIG. 39 is a first perspective view thereof; and
FIG. 40 is a second perspective view thereof;
FIG. 41 is a front elevational view of a sixth embodiment of
a battery of the design;
FIG. 42 is a rear elevational view thereof;

FIG. 43 is a top plan view thereof;
FIG. 44 is a bottom plan view thereof;
FIG. 45 is a right side elevational view thereof;
FIG. 46 is a left side elevational view thereof;
FIG. 47 is a first perspective view thereof; and
FIG. 48 is a second perspective view thereof;
FIG. 49 is a front elevational view of a seventh embodiment
of a battery of the design;
FIG. 50 is a rear elevational view thereof;
FIG. 51 is a top plan view thereof;
FIG. 52 is a bottom plan view thereof;
FIG. 53 is a right side elevational view thereof;
FIG. 54 is a left side elevational view thereof;
FIG. 55 is a first perspective view thereof; and,
FIG. 56 is a second perspective view thereof.

The ornamental design which is claimed is shown in solid
lines in the drawings. Any broken lines in the drawings are
for illustrative purpose only and form no part of the claimed
design. (Said broken lines appear in FIGS. 3-5, 7-8; FIGS.
11-13, 15-16; FIGS. 19-21, 23-24; FIGS. 27-29, 31-32;
FIGS. 35-37, 39-40; 43-45, 47-48; FIGS. 51-53, 55-56.)
